SAWHORSE BRACKET

Roy F. Thompson, Longmont, Colo.

Application September 14, 1956, Serial No. 42,931

Term of patent 14 years

(Cl. D93—2)

Fig. 1 is a perspective view showing the top, one side and one end of a sawhorse bracket showing my new design; and

Fig. 2 is a similar perspective view showing the other side and other end thereof.

I claim:

The ornamental design for a sawhorse bracket, as shown.
